(57) **CLAIM**

The ornamental design for a dispensing apparatus, as shown and described.

DESCRIPTION

FIG. 1 is a front perspective view of a dispensing apparatus of the present invention;

FIG. 2 is a top plan view thereof;

FIG. 3 is a front view thereof;

FIG. 4 is a bottom plan view thereof;

FIG. 5 is a rear view thereof;

FIG. 6 is a right side view thereof; and,

FIG. 7 is a detailed perspective view of an individual dispenser of the dispensing apparatus with the dispensing apparatus removed for ease of illustration.
